FORK OR SIMILAR ARTICLE

Björn Wiinblad, Selb, Bavaria, Germany, assignor to Rosenthal-Porzellan Aktiengesellschaft, Bavaria, Germany, a corporation of Germany

Filed May 2, 1961, Ser. No. 65,006

Term of patent 14 years

(Cl. D54—12)

The dominant features of my design reside in the portions shown in full lines on the drawing.

I claim:

The ornamental design for a fork or similar article, as shown and described.
